DESIGN FOR A SHOE

Curt Kliche, New York, N. Y.

Application May 5, 1939, Serial No. 84,813

Term of patent 3½ years

To all whom it may concern:

Be it known that I, Curt Kliche, a citizen of the United States and resident of New York city, in the county of Queens and State of New York, have invented a new, original, and ornamental Design for a Shoe, of which the following is a specification, reference being had to the accompanying drawing, forming part thereof, in which,

Fig. 1 is a plan view of the shoe showing my new design, and

Fig. 2 is a side view of the shoe shown in Fig. 1.

I claim:

The ornamental design for a shoe, as shown.

CURT KLICHE.
